(57) **CLAIM**

The ornamental design for a faucet as shown and described.

DESCRIPTION

FIG. 1 is a front, left and top perspective view of a faucet showing my new design;

FIG. 2 is a left view thereof;

FIG. 3 is a right view thereof;

FIG. 4 is a rear elevational view thereof;

FIG. 5 is a front elevational view thereof;

FIG. 6 is a top plan view thereof;

FIG. 7 is a bottom plan view thereof;

FIG. 8 is a rear, right and bottom perspective view thereof; and,

FIG. 9 is a perspective view of a faucet, shown in an environment of use.

The broken lines in FIG. 9 illustrating a faucet, depict environmental subject matter that forms no part of the claimed design. The remaining broken lines depict portions of the faucet and form no part of the claimed design.

1 Claim, 9 Drawing Sheets
